C. A. Shandless

UNITED STATES PATENT OFFICE.

GEORGE WASHINGTON HADESTY, OF DRIFTON, PENNSYLVANIA.

TAMPING-BAR.

SPECIFICATION forming part of Letters Patent No. 337,492, dated March 9, 1886.

Application filed January 16, 1886. Serial No. 188,771. (No model.)

To all whom it may concern:

Be it known that I, GEORGE WASHINGTON HADESTY, a citizen of the United States, residing at Drifton, in the county of Luzerne and State of Pennsylvania, have invented a new and useful Improvement in Tamping-Bars, of which the following is a specification, reference being had to the accompanying drawings.

10 My invention relates to an improvement in tamping-bars to be used in blasting and mining; and it consists in the peculiar construction and combination of devices, that will be more fully set forth hereinafter, and particularly pointed out in the claims.

15 In the drawings, Figure 1 is an elevation of my invention in position for use and extended to its full length. Fig. 2 is a vertical longitudinal sectional view of the same contracted. 20 Figs. 3 and 4 are transverse views taken on the lines xx and yy , respectively.

25 In blasting rock and coal in mining it is usual to drill the hole, place the powder or other explosive therein, and then place dirt or sand on the powder in the hole, and tamp it firmly therein before igniting the explosive, in order to cause it to explode with sufficient violence to shatter the rock or coal bed.

30 The object of my invention is to provide an apparatus for tamping the dirt or sand more expeditiously than has been heretofore done.

35 A represents a cylindrical tube of any suitable diameter and closed at one end. On one side of the tube is a slot, B, which extends nearly the entire length of the tube, and on the opposite side is a shorter slot, C. A notch, D, communicates with the slot B at a suitable distance from the closed end of the tube, and the said tube is also provided with stops E.

40 F represents a cylindrical case, which is open at both ends and fits on the closed end of the tube. A transverse bar, f, passes through the inner end of the case F, and extends transversely through the tube and works

45 in the slots B C. A rod, f' , is attached to the bar f , extends through the tube for a suitable distance, and has its outer end bent at right angles, as at f'' , and extending out through the slot B. A coiled retractile spring, G, in the tube

50 A, has one end attached to the outer end of the bar f' and its other end attached to the

open end of the tube A. By this construction it is plain that the case F can be drawn outwardly on the closed end of the tube telescopically and against the tension of the spring, as shown in Fig. 1, and maintained in that position by pressing the end f'' of the rod f' , which forms a detent, into the notch D.

When the hole is drilled and the charge of explosive inserted, the extended case F is filled with earth and inserted in the hole, and held therein with one hand, and the miner releases the detent from the notch D, which causes the spring to force the closed end of the tube through the case F and discharge the earth contained in the case into the drilled hole and onto the explosive contained therein. As soon as the earth is discharged into the hole, it is then pressed or tamped firmly therein by pressing upon the outer end of the tube and before withdrawing it from the hole. The operation of filling and tamping the hole is thus performed very expeditiously.

A concave groove, e, is made in one side of the case F, coincident with a similar groove in the closed end of the tube. The function of the groove e is to receive the blasting-fuse, as shown in Fig. 2. The closed end of the tube forms a plunger, working in the case F.

Having thus described my invention, I claim—

1. In a tamping-bar for drill-holes, the combination of the case F and the spring-actuated plunger therein, for the purpose set forth, substantially as described.

2. In a tamping-bar for drill-holes, the combination of the case F, the spring-actuated plunger therein, and the detent to lock the plunger to the case when the plunger is extended, substantially as described.

3. In a tamping-bar for drill-holes, the combination of the case having the groove e in its side to receive the fuse, and the plunger working in the case, for the purpose set forth, substantially as described.

In testimony that I claim the foregoing as my own I have hereto affixed my signature in presence of two witnesses.

GEORGE WASHINGTON HADESTY.

Witnesses:

ELLIOTT A. OBERRENDER,
GEORGE A. SOLT.
